ALL-WEATHER DOORSILL SEAL

Filed Oct. 16, 1951

UNITED STATES PATENT OFFICE

2,617,161

ALL-WEATHER DOORSILL SEAL

Stewart T. Oswald, Fort Lauderdale, Fla.

Application October 16, 1951, Serial No. 251,531

5 Claims. (Cl. 20—65)

1

This invention relates to an all-weather door-sill seal.

An object of the invention is the construction of an efficient device which will cause a seal on the floor or a seal against a door-sill, for the purpose of keeping out driving rains, snows, and cold air.

Another object of the invention is the construction of an efficient device that can be positioned in different places, such as a door that opens outwardly, or a door that opens inwardly.

A still further object of the invention is to produce an efficient device that will fit tightly the door and jamb, as well as sealing the door against drafts and other disagreeable conditions. Further, this device will function with or without a door-sill.

The invention of this application is an improvement upon the invention disclosed in my United States Patent No. 2,565,393, issued August 21, 1951.

With the foregoing and other objects in view, this invention comprises certain novel constructions, combinations, and arrangements of parts as will be hereinafter fully described, illustrated in the accompanying drawings, and more particularly pointed out in the appended claims.

In the drawings:

Figure 1 is a view in front elevation of a device constructed in accordance with this invention, showing same applied to a door that is intended to swing inwardly.

Figure 2 is a fragmentary end view of a door frame and a door to which my invention is applied.

Figure 3 is a view in end elevation of the device in a closed position.

Figure 4 is an enlarged sectional view, taken on line 4—4, Fig. 1, and looking in the direction of the arrows.

Figure 5 is a view similar to Figure 1, showing a modified form of the device applied to a door that is adapted to swing outwardly.

Figure 6 is a view in end elevation, showing the door frame and door with my device applied thereto, in an open position.

Figure 7 is a view in end elevation, showing the device of Figure 6 in a closed position.

Referring to the drawings, in which the preferred specie of this invention is shown in Figures 1 to 4, 1 designates the door frame and 2 the inwardly swinging door.

The device comprises a sectional casing 2a consisting of a cover plate 3 and a back plate 4. These two plates are held together by screws 5.

2

Fig. 1. The back plate 4 is provided near its center with a vertical slot 6, Fig. 4. Within the sectional casing 2a is a split rotatable cylinder or sleeve 7. This sleeve 7 is provided with a transverse slot 8. A comparatively flat spring 9 has its upper end in slot 6. The lower portion of spring 9 is in the slot 8 and presses against the lower end of the slot, as clearly shown in Fig. 4. An elongated seal 10 is mounted on the split sleeve 7 and extends the entire length of said sleeve. The seal 10 is provided with transversely spaced longitudinal grooves 10a selectively engageable by one edge of said split. This structure permits adjustment of seal 10 in and out of the sleeve 7.

A nut 11 is placed in the upper portion of slot 6, with the spring 9 bearing against same. A screw 5 extends through the upper portion of the cover plate 3 and through spring 9 and the nut 11, whereby the spring 9 is held in an excellent position.

The rotatable sleeve 7 is provided on its ends with lugs 12, which are adapted to engage adjustable screws 13. When the door 2 is moved to a closed position, the lug 12 comes in contact with the screw 13, resulting in the sleeve being rotated, from the position shown in Fig. 2 to the closed or sealing position shown in Fig. 3. As soon as the door is beginning to move to an open position, the spring 9 will begin to rotate the sleeve 7, whereupon the seal 10 will begin to move upward until it is in its open position, as shown in Fig. 4.

The embodiment shown in Figures 5 to 7, is substantially the same with reference to the spring construction, as described for the embodiment of Figures 1 to 4. In this embodiment, the lugs or triggers 12a are placed in a relatively higher position on the ends of the rotatable sleeve 7, and the screw 13a is also placed parallel on the door frame 1 so that the trigger or lug 12a will strike against the screw 13a, causing the seal 10 to be moved to a closed or sealing position when the door is entirely closed. On the outer ends of the back plate 4a are formed right-angled brackets 14. These brackets 14 serve to hold the rotatable sleeve securely within the sectional casing.

One of the advantages of my construction is that the seal can be cut off at either end to fit a job, irrespective of the width of the door. This can be more readily accomplished when using the seal device of Figures 1 to 4.

While I have described the preferred embodiments of the invention and illustrated the same

in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In a device of the class described, the combination of a sectional casing comprising a cover plate and a back plate, said back plate provided with a transverse slot, a rotatable split sleeve in said casing, said sleeve provided with a slot registering with said first-mentioned slot, a spring fastened to said casing and positioned in said registering slots and exerting pressure at all times on said sleeve, and said sleeve being provided with a seal, said seal consisting of an elongated strip extending through the split of the sleeve and provided with transversely spaced longitudinal grooves selectively engageable by one edge of said split.

2. In a device of the class described, the combination of a casing provided in its back with a vertical slot, a rotatable split sleeve in said casing, said sleeve provided with a slot registering with said first-mentioned slot, a spring fastened to said casing and positioned in said registering slots and exerting pressure at all times on said sleeve, and said sleeve being provided with a seal, said seal consisting of an elongated strip extending through the split of the sleeve and provided with transversely spaced longitudinal grooves selectively engageable by one edge of said split.

3. In a device of the class described, the combination of a casing, a rotatable split sleeve within said casing, a spring mounted on said casing and extending into said sleeve, said spring at all times exerting pressure on said rotatable sleeve, and a seal carried by said rotatable sleeve, said seal consisting of an elongated strip extending through

the split of the sleeve and provided with transversely spaced longitudinal grooves selectively engageable by one edge of said split.

5. In a device of the class described, the combination of a sectional casing, a comparatively flat spring secured between the sections of said casing, a rotatable split sleeve within said sectional casing, said rotatable sleeve provided with a slot, said spring extending into said slot and exerting continuous pressure upon said sleeve, and a seal carried by said sleeve, said seal consisting of an elongated strip extending through the split of the sleeve and provided with transversely spaced longitudinal grooves selectively engageable by one edge of said split.

10 20 25 5. In a device of the class described, the combination of a casing provided with right-angled brackets extending from the back of said casing, a rotatable split sleeve within said casing, a spring carried by said casing and pressing continuously against said sleeve, and a seal carried by said sleeve, said seal consisting of an elongated strip extending through the split of the sleeve and provided with transversely spaced longitudinal grooves selectively engageable by one edge of said split.
